(No Model.)

T. G. SPRINGER.

PROCESS OF AND APPARATUS FOR MANUFACTURING GAS.

No. 314,739.

Patented Mar. 31, 1885.

UNITED STATES PATENT OFFICE.

THEODORE G. SPRINGER, OF NEW YORK, N. Y.

PROCESS OF AND APPARATUS FOR MANUFACTURING GAS.

SPECIFICATION forming part of Letters Patent No. 314,739, dated March 31, 1885.

Application filed November 15, 1884. (No model.)

To all whom it may concern:

Be it known that I, THEODORE G. SPRINGER, of the city of New York, in the county of New York and State of New York, have invented 5 certain new and useful Improvements in Processes of and Apparatus for Manufacturing Gas; and I do hereby declare that the following is a full, clear, and exact description of the invention, which will enable others skilled in 10 the art to which it appertains to make and use the same, reference being had to the accompanying drawings, and to the letters of reference marked thereon, which form part of this specification.

15 This invention relates more particularly to the process and apparatus for uniformly carbureting water-gas with hydrocarbon vapor and forming a fixed illuminating-gas by forcing hot water-gas in numerous small jets or 20 streams into the passing current of hydrocarbon vapor, then passing the mixture through the fixing-chamber in the reverse direction to that in which the hot products of combustion were passed for heating the fixing-chamber, 25 and subjecting the mixture to a progressively-increasing temperature in such fixing-chamber, thereby preventing carbonization of oily matter or formation of lamp-black, and consequent waste of hydrocarbon oil or vapor; and 30 the invention embraces improvements upon processes and apparatus covered by patents heretofore granted to me.

The hot water-gas and hydrocarbon oil or 35 vapor may be combined in any known manner with the hot water-gas, and the mixture then passed through the fixing-chamber in the reverse direction to that in which the fixing-chamber was heated.

40 The improvements will be disclosed in the description of the construction and operation of the apparatus, and will be particularly pointed out in the claims.

In the accompanying drawings, Figure 1 represents a longitudinal vertical section of my 45 improved gas-generating apparatus. Fig. 2 represents a sectional detail view of a modified form of the gas and hydrocarbon-vapor mixing pipes.

The fuel and steam decomposing chamber 50 A is built of brick with an iron jacket, in the usual manner, and has the usual opening, S,

and lid s for charging in the fuel. A grate, a, separates the fuel-chamber from the closed ash-box A'', which is made hopper-shaped, and has a tight-fitting door or valve, a', closing its contracted lower end. Ash-box A'' may be made of metal, as cast-iron, and projects into the ash-chamber A', inclosed by a downward extension of the furnace walls. This lower ash-chamber should have a door in its 60 wall opening to the external air. Air-blast pipe V, having valve x and connecting with an air-forcing engine or blower, conducts air to the fuel below the grate through the medium of annular flue T and ports t. Air-blast pipe 65 V', having valve x', also connects with the top of fuel-chamber A. An escape-pipe, C, for heating gas, connects the top of fuel and decomposing chamber A with the top of fixing-chamber B. A water-cooled valve-box, C', 70 and contained valve c are connected in pipe C. The valve c fits up against a seat around the inlet portion of pipe C at the top of the box, and has a stem, c', passing down through a stuffing-box in the bottom of the box, and is 75 operated by a pivoted lever. Inlet water-pipe h connects with pipe C above the valve, and outlet water-pipe h' connects with such pipe above the valve, and also with the box below the valve, and a trap-overflow pipe, h'', connects with the box, all as shown. Steam-pipe K, having valve k, connects with pipe C above the valve for supplying steam to the top of the fuel and steam-decomposing chamber. The outlet-pipe D for water-gas connects the 80 base of the fuel-chamber, through the medium of annular flue T and ports t, with the base of the fixing-chamber B through the medium of the peculiarly constructed and arranged pipes described below. Pipe D connects with the 85 tapering perforated pipe D', which projects into and through the large surrounding hydrocarbon-vapor pipe I, which opens freely at its inner end into the base of the fixing chamber. Pipe H, for supplying hydrocarbon va- 90 por from a suitable vaporizing device, connects with the end of vapor-pipe I, projecting outside of the fixing-chamber, and the vapor passing through pipe I surrounds the perforated pipe D', which delivers water-gas in numerous 95 small jets through its length into such surrounding and inflowing hydrocarbon vapor,

so that the gas and vapor are uniformly and thoroughly mixed together preparatory to conversion into a fixed illuminating gas.

Good results in mixing gas and vapor may be secured by laying the gas and vapor flues side by side, with a perforated partition plate or wall between them, so arranged as to form a tapering gas-flue, and so that the water-gas will be delivered in numerous small jets into the inflowing hydrocarbon vapor, as represented in the modification shown in Fig. 2.

The naphtha or other hydrocarbon fluid is to be vaporized in a long cylindrical pipe or chamber supplied with steam-heating pipes or a coil. The naphtha may also be vaporized by passage through a pipe or pipes laid in the water-gas flue by the heat of the water-gas, and the vapor then delivered into the vapor-flue surrounding or extending alongside of the perforated gas-flue. Pipe D has a controlling-valve, *l*, provided with a stem, *l'*, passing up through a stuffing-box and connected to a pivoted operating-lever. Vapor-pipe H is also provided with a controlling-valve, *i'*.

The fixing-chamber B is constructed of brick, and covered by an iron jacket in the usual manner. It is provided at the top with man-hole P, having tight lid or cap *p*, with air-inlet pipe V", opening adjacent to the pipe C, admitting heating-gas, and with pipe E, for conducting off the illuminating-gas to the hydraulic seal-box, from which it is to be passed through the purifiers and to the holder in the usual way. The upper portion of the fuel and decomposing chamber A has numerous portions of refractory brick or tiles, R, projecting several inches into the chamber, which greatly increase the heating-surface and absorb heat while the fuel is being raised to incandescence, and which afterward serve to superheat steam.

Fixing-chamber B is filled with refractory brick loosely laid and supported upon the perforated arch *b*, near the bottom of the chamber, in the usual manner. Below such arch connects outlet-pipe F, having hinged cap or lid *f*, for the escape of products of complete combustion. The hydrocarbon-vapor pipe I extends below the arch and opens into the chamber by passage *i'*, through which the mixed water-gas and hydrocarbon vapor pass up into the heated refractory brick-work to be fixed. The fixing-chamber is to be supported on a suitable foundation of masonry or on iron columns at about the same level as the fuel and decomposing chamber. This of itself is often advantageous, where the building in which the generator is set up is not of sufficient height to admit of the two chambers being placed one above the other in a vertical column, as shown in patents previously granted to me.

Other advantages of the construction and arrangement shown will appear in the description of the operation of the apparatus, as follows: After the fire is kindled and a sufficient quantity of fuel fed into chamber A the ash-

pit doors are closed, lids *s* and *p* are closed, valve *l* in pipe D and valve *i* in pipe H are closed, valve *c* in connecting-pipe C and cap *f* in smoke-escape pipe F are opened, and the air-blast is admitted to the base of the fuel by opening valve *x*, and is continued till by combustion the fuel is heated to incandescence to a distance of several feet from the grate. The resulting hot gaseous products, containing a valuable percentage of carbonic oxide, are at the same time passed through pipe C into the top of chamber B, where they are completely burned by the admission of an air-blast through pipe V", the hot products of combustion passing down through the refractory brick-work and highly heating it at the upper portion and gradually heating it to a lower temperature toward the lower portion, so that the bottom portion of such brick-work and of chamber B, where the gas and oil-vapor are admitted, are only moderately heated, and a better result thereby secured, in uniformly mixing the gas and oil-vapor and forming a fixed gas, without the wasteful formation of lamp-black. The waste products finally escape through pipe F.

If desired, an air-blast may be admitted for a short period through pipe V' to the top of chamber A, to cause combustion for heating the brick-work above the fuel, to be afterward utilized in superheating steam. The fuel and the fixing chamber being suitably heated, the air-blasts are shut off, valve *c* and cap *f* are closed, valve *l* is opened, and steam is let into the top of the fuel-chamber by opening valve *k* in steam-supply pipe K, which opens into pipe C. The steam is superheated in the top of chamber A and in the upper portion of the fuel, and is completely decomposed by passage down through the incandescent portion of the fuel, and the resulting water-gas passes out through ports *t*, annular flue T, pipe D, and perforated pipe D' into the vapor-pipe I. The hydrocarbon vapor at the same time is admitted into pipe I and flows around perforated pipe D', so that the hot water-gas is passed gradually and in numerous fine jets, and mingles with the inflowing oil-vapor, thereby gradually and uniformly heating up such vapor and preventing the formation of lamp-black. The commingled gas and vapor now pass into the cooler portion of the brick-work, becoming uniformly combined, and thence on into the hottest brick-work, where a homogeneous fixed gas is formed. The oil-vapor being first subjected to the cooler portion of the brick-work, has opportunity to expand and thoroughly diffuse itself through the water-gas before it can be burned and turned to lamp-black, and oil is thus economized and better results secured. The two ash-chambers, with a valve or door between them, permit the ash to be cleaned out without interfering with the operation of the generator. The means for cooling valve *c* and box C form no part of my invention in this

application. The fixed illuminating-gas passes by pipe E to the hydraulic seal-box, (not shown,) from which it passes through the purifiers to the holder in the usual manner.

5 The operations of heating up the apparatus and making gas are conducted alternately in the usual manner.

Having described my invention, what I claim, and desire to secure by Letters Patent, 10 is—

1. The process of generating gas, which consists in decomposing steam in contact with incandescent or highly-heated fuel, and forcing the resulting hot water-gas in numerous fine 15 jets or streams into a passing current of inflowing hydrocarbon vapor, whereby such vapor is gradually and uniformly heated and mixed with the water-gas, and then converting the mixture into a fixed gas.

20 2. The process of manufacturing illuminating-gas, which consists in decomposing steam in contact with highly-heated fuel, and forcing the resulting hot water-gas in numerous fine jets or streams into a current of inflowing 25 hydrocarbon vapor for gradually and uniformly heating such vapor, mixing the two together, then subjecting the mixture to a comparatively low temperature and to a gradually-increasing temperature till a homogeneous 30 fixed gas is produced, whereby the formation of lamp-black is prevented and improved results are secured.

3. In combination with the decomposing-chamber, a gas-outlet pipe or flue having numerous small perforations, and an adjacent vapor pipe or flue with which such perforations communicate, an inlet vapor-pipe, and a connecting receiving-chamber.

4. In combination with a gas-generator, a 40 perforated discharge-pipe, a surrounding vapor-pipe, an inlet-pipe for conveying hydrocarbon vapor connected with such surrounding vapor-pipe, and a connected fixing-chamber.

45 5. The combination of decomposing-chamber A, fixing-chamber B, a pipe having a con-

trolling-valve connecting them at the top, a pipe having a controlling-valve connecting them at the bottom, an escape-pipe for gas leading from one end of the fixing-chamber, 50 and an escape-pipe for waste products of combustion leading from the other end of such chamber, and suitable connecting-pipes for air, steam, and oil or oil-vapor.

6. The chambers A and B, connected at top 55 and bottom by pipes having controlling-valves, outlet gas-pipe E, and escape-pipe F for products of combustion connected, respectively, with the top and bottom of chamber B, in combination with a perforated water-gas 60 conduit communicating with and discharging into a hydrocarbon-vapor pipe arranged at the base of the fixing-chamber, for the purpose described.

7. The process of manufacturing gas, which 65 consists in blasting a body of fuel with air in one direction till it is highly heated, then superheating and decomposing steam by passing it first into the cooler portion of the fuel and then through the hottest portion thereof 70 in a direction the reverse of that traversed by the air-blast, and forcing the resulting hot water-gas in numerous streams or jets into a passing current of hydrocarbon vapor or oil, whereby such vapor or oil is gradually heated 75 and mixed with the water-gas, and then converting the same into a fixed illuminating-gas.

8. In combination with a gas-generator, a gas-discharge pipe of tapering form having numerous perforations in one or more of its 80 walls, and an adjacent hydrocarbon-vapor pipe or flue with which such perforations communicate, an inlet vapor-pipe, and a connecting fixing-chamber, for the purpose described.

In testimony that I claim the foregoing as 85 my own I affix my signature in presence of two witnesses.

THEODORE G. SPRINGER.
